UNITED STATES PATENT OFFICE.

RICHARD B. REED, JR., OF ORANGE, CALIFORNIA.

DEVICE FOR EMBEDDING WIRES IN FUSIBLE SHEETS.

Application filed May 18, 1921. Serial No. 470,548.

To all whom it may concern:

Be it known that I, RICHARD B. REED, Jr., a citizen of Canada, residing at Orange, in the county of Orange and State of California, have invented a new and useful Device 5 for Embedding Wires in Fusible Sheets, of which the following is a specification.

The device is more particularly adapted to be used in the bee industry in embedding 10 wires in honeycomb foundations.

In common apiary practice, frames are provided in each of which is secured a sheet of wax, that is supported by the frame and is reinforced by strands of wire extending 15 lengthwise of the frame, and embedded in the wax. The sheets form the foundations on which the bees build the honeycomb cells. The several strands are parts of a single 20 length of wire which is threaded through apertures in the frame, and is secured at its ends to suitable fastening means. There are usually four of these strands to each frame and consequently both ends of the wire of which they are formed are secured 25 to the same end of the frame.

Objects of my invention are to construct a device for embedding the strands of wires in the wax which may be operated with a minimum amount of time and labor, 30 and which will give the greatest freedom to the hands of the operator so that he may smooth out the wax and eliminate irregularities and unevenness therein.

The above objects are accomplished by 35 providing a block which is adapted to support a honeycomb frame and which is movable to and fro in a fixed path; and by providing positive and negative electrical contact members adjacent one end of said path, 40 so placed that they will contact respectively with the ends of the wire in the frame when the block is moved to that end of its path. When the contact members are in contact with the ends of the wire a current of elec- 45 tricity may be passed through the wire, heating the same and melting the wax adjacent thereto and allowing the wire to sink in and become embedded in the wax.

Honeycomb frames are usually cheaply 50 made and the parts thereof are not always true; and it is an object of the invention to provide means whereby the electrical contacts may adjust themselves to any irregularities or unevenness due to the faulty con- 55 struction of the frame.

It is frequently desirable to use electricity from a source of high voltage and in that case a transformer may be used to lower the potential between the contacts, and in order to economize electrical energy 60 a switch may be provided whereby current may be turned off when the contact members are not in contact with the ends of frame wires and it is desirable that the switch may be so constructed and arranged that 65 it may be operated while at the same time leaving the hands of the operator free to manipulate the block and frame.

It is an object of the invention to provide means, operable otherwise than by the hands 70 whereby the circuit through the transformer may be made or broken.

Another object is to so construct the device that it may be readily dis-assembled and compactly packed for transportation. 75

Another object is to provide means whereby the electrical contact members may be adjusted to the requirements of the varied wiring of the frames to be used with the device. 80

Another object is to provide means which will cause the wires to become simultaneously and evenly embedded in the wax.

Another object of the invention is to provide means to automatically form an electric circuit when the block is moved to position with the terminals of the wire in the honeycomb frame contacting with the contact members. 85

Another object of the invention is to provide means for preventing the damaging of parts of the device resulting from lateral displacement of the block relative to the rollers.

Other objects, advantages and features of 90 invention may appear from the accompanying drawing, the subjoined detail description and the appended claims.

The accompanying drawing illustrates the 95 invention.

Figure 1 shows the device placed on the table with the movable block in part broken away to show the rollers and the relation of the block to the contact members when the block is in normal or retracted position; 100 the view also showing the relation of the transformer and switch mechanism to the contact members.

Fig. 2 shows in perspective a honeycomb 105 frame.

Fig. 3 is a longitudinal sectional view on line x^3 , Fig. 4, of the device showing a honeycomb frame mounted thereon and in position of contact with the contact members, also showing the spring for retracting the movable block.

Fig. 4 is a plan view of the device in the position as shown in Fig. 3 and showing the wiring of the honeycomb frame.

10. Fig. 5 is a detail view of one of the contact members and the supporting structure therefor.

Fig. 6 is a detailed view showing the specific switch member.

15. Fig. 7 shows in perspective the glass plate to be used in connection with the device.

Fig. 8 is a plan view of a different form of the device showing guide members for the block and also showing the transformer 20 attached to the base.

Fig. 9 is a longitudinal sectional view of the device taken on line x^9 , Fig. 8, showing an electrical switch mounted on the base, and a control on the block for causing the switch members to contact; the block being shown in its forward position and the switch members contacting.

Fig. 10 is a fragmentary section similar to the section shown in Fig. 9 showing the 30 position of the contact members relative to each other, when the block is in its retracted position.

Fig. 11 is a cross section on line x^{11} , Fig. 9, showing the switch members and control; 35 and the position of the block in the groove between the guide members.

Before describing my invention in detail I will set forth the nature of one type of 40 honeycomb frame with which the invention is to be used. Referring to Fig. 2 in which the frame is illustrated, A and B are respectively the side and end members of the frame, which is rectangular in shape. Threaded back and forth longitudinally of 45 the frame is a wire C the strands c of which are parallel to each other. The ends of the wire are secured to one end of the frame by nails D or other suitable means. Secured within the frame by one edge is a sheet of 50 wax E into which the strands c of the wire are to be embedded. The device by which this is to be accomplished will now be described.

Referring to Fig. 1, 1 designates a table 55 or support of any character on which the device may be placed; the table being no part of the invention. 2 is a base member of the device on the upper side of which are secured the brackets 3; the brackets being 60 provided with journals 4 in which suitable rollers 5 are rotatably mounted.

Mounted on the rollers is a block 6, provided in its under surface with a rectangular recess 7; the recess being of a length considerably greater than the distance between 65

the rollers 5, and of a width sufficient to receive the rollers which extend transversely of the recess. When the block is mounted on the rollers, the rollers are received within the recess 7; the side and end walls 8 and 9 of the recess extending down about the rollers; the side walls 8 preventing lateral movement of the block and end walls 9 determining the length of the path of travel of the block. The block is preferably held 75 slightly elevated by the rollers above the base members thereby eliminating friction between the block and base in the movement of the block back and forth along its path. A spring 10 may be provided, attached by one end to the base 2 and by the other to block 6 whereby the block may be normally held retracted and out of contact with the contact members which I will now describe.

At one end of the base member adjacent the path of travel of block 6 and spaced apart transversely of said base member are posts 11 and 12 having rectangular apertures 13 therein, and in the apertures are slidably mounted stems or rods 14. On the 80 ends of the stems or rods are secured by means of pivots 15 contact plates 16 and 17. The arrangement of the pivots being such that the plates may swing in a horizontal plane to insure contact with members D 95 when any portion of the plates contact with the end frame member B and the posts are so placed that, when the block 6 is moved to that end of its path of travel, the contact plates 16 and 17 will respectively come in 100 contact with the ends of the frame member B. The rods 14 are rectangular in cross section and are adapted to fit snugly in apertures 13 whereby turning movement of the rods is prevented.

Surrounding the stems or rods 14 are compression springs 18 which abut at one end against the posts 11 and 12 and at their opposite ends against a pin 19. By this arrangement the contact plates are yieldably held extended toward the block 6 and by means of said springs together with the pivotal mounting of the contact plates 16 and 17, the contact plates are adapted to adjust themselves to any irregularity or imperfection in construction of the honeycomb frame. The posts 11 and 12, the stems 14 and the plates 16 and 17 are of electrically conductive material, and the supports are connected with a source of electric energy through the 110 conductors 20 and 20^a.

In order that the contact members may be adjusted to any position of the terminals D of the wire C at the end of the frame the posts 11 and 12 are preferably mounted for adjustment transversely of the base toward and away from each other and for this purpose the lower portions of the posts are made cylindrical forming stems 21, having heads 22, on their lower ends. The heads may be 125

formed integral on the pins or may be in the form of nuts, screw threaded onto the ends of the stems as shown.

- The stems are adapted to slide in slots 23, 5 23^a extending transversely of the base 2 from the sides of the base and toward each other, the heads 22 riding in slideways 24, formed on the underside of the block and communicating respectively with the slots 23, 23^a.
 10 The stems 21, 21^a are screw threaded and lock nuts 25 are provided thereon by which the posts may be secured in adjusted position. Washers 26, 26^a may be employed between the nuts 25, 25^a respectively and the 15 base to prevent wear on the base in adjusting the nuts. The adjacent ends of the slots 23, 23^a are spaced from each other a sufficient distance to, at all times, prevent the posts 11 and 12 from contacting with each 20 other. The slots and slideways may be provided with linings 27 of brass or other electrically conductive material, forming an electrically conductive connection between the posts 11 and 12 and conductors 20 and 20^a 25 respectively.

A transformer 28 is shown introduced in the circuit 29 leading from the source of electric energy to the contact plates 16, 17 to reduce the electro-motive force of the current. In connection with the transformer a switch 30 may be employed, one contact 31 of which is attached to a treadle 32 operable by the foot; and the other contact 34 is secured to a base 35 to which the treadle is 30 hinged; the contact members being normally held out of contact by means of spring 36. By this arrangement of the switch the operator's hands are left free at all times for manipulation of the block and the sheet of 35 wax within the honeycomb frame.

It will be understood that a battery or any other suitable source of electricity may be used in connection with the contact device.

The slip connections 37, 37^a and 38, 38^a 45 may be provided by which the conductors 20, 20^a and the base 2 and conductors 29 and the switch 30 may be disconnected when the device is not in use. The posts 11 and 12 may be detached from the base and the parts 50 of the device may be compactly packed for transportation from place to place.

In operation, a honeycomb frame with a sheet of wax secured therein, as set forth above, is placed on the movable block 6 55 with the wax lying between the block and the wire strands *c*. The operator then, with one hand, moves the block against the force of spring 10 until the terminals D contact with the contact members 16 and 17 60 when the operator places his foot on the treadle passing a current of electricity simultaneously through all the strands of the wire of the frame heating the wire, and melting the wax adjacent thereto. When the 65 wax is sufficiently soft the strands of wire

will sink into the body thereof and upon the wax becoming cool again the wires will be firmly embedded in the wax forming a reinforce therefor. With his other hand, the operator may smooth out any buckling 70 or irregularity in the wax and is enabled to obtain a uniform embedding of the wires. When the wires have sunk into the wax a sufficient distance the operator may move the block to the opposite end of its path of travel or may remove his hands and allow the block to travel backward under the force of the contractile spring 10. As a variation from the above operation, the uniform embedding of the wires in the wax may be accomplished by placing a plate 39 on top of the wire strands *c*, *c* after the frame has been placed on the block, said plate pressing the wires into the wax when the latter is softened by heat. The plate 39 is preferably 80 of glass or other transparent material so that the operator may observe the embedding of the wires.

The plate should be of such shape and size as to fit readily within any honeycomb frame 90 with which the device is to be used and should be of sufficient width to rest simultaneously on all of the wires. Handles 40 are provided at the ends of the plate by which it may be placed upon, or taken off 95 the wires.

By means of the above described arrangement the strands of wire are embedded simultaneously in the wax with a great saving of time and labor. The work may be quickly 100 done and at the same time more uniform embedding of the wires in the wax may be obtained than has heretofore been possible.

The device as illustrated in Figs. 8 to 11 inclusive, differs from that shown in Figs. 105 1 to 7 inclusive, only in the arrangement of the transformer on the base 2; in the provision of a switch 41 operable by the movement of the block in its path of travel; and in the provision of spaced guide members 110 42 and 43 extending parallel with the path of travel of the block and adapted to prevent lateral movement of the block relative to the path of travel.

The switch 41 comprises a rigid member 115 44 and a flexible member 45 mounted on the base; the flexible member being normally out of contact with the rigid member. Secured to the movable block 6 is a control device 46 having a sloping surface 47 adapted to ride upon the flexible member, to cause it to contact with the rigid member, when the block is moved to the forward end of its path of travel. With this construction, the device is very compact and may be readily 120 transported from place to place and set up for operation, all the parts being attached to the base member 2; and may be operated by persons of little skill; the switch being operable by the movement of the block into 125 130

position for the ends of the wire *c* of the frame to contact with contact members 16 and 17.

By the cooperation of sides 8 and the 5 guide members 42, 43 lateral movement of the block on the rollers is prevented and injury of the block and rollers due to such side movement is avoided.

The advisability of disconnecting the 10 transformer with the source of electric energy arises from the fact that transformers at present in use consume energy so long as they are connected with the electrical source. This energy is transformed into heat meters 15 taken up by a vibrator inside the transformer intended to prevent such over-heat. The switches 30 and 41 disconnect the transformer to avoid using current in the transformer except at the moment of embedding.

20 I claim.

1. A device for embedding wires strung in a frame, in wax, comprising a base; rollers rotatably mounted thereon; a block having a recess in its lower side, and adapted to 25 receive said rollers, the relation of said rollers in said recess being such as to afford limited movement of said block relative to the base; contacts adjacent one end of the path of movement of the block adapted to 30 contact with said wire so as to pass a current of electricity therethrough; said contacts being slidably mounted and spring pressed whereby the contacts adjust themselves to irregularities of said frame.

35 2. In a device for embedding, in a wax foundation strands of wire strung in a frame a movable block; and electric contacts comprising a pair of apertured uprights and rods slidable in said apertures, 40 and held against displacement therefrom; contact plates on the ends of said rods to contact with the ends of the wire; and springs on the rods between said plates and uprights.

45 3. A device for embedding strands of wire strung in a frame in a wax foundation, comprising a movable block and electric contacts; said contacts comprising a pair of apertured uprights; rods slidable in said apertures and held against displacement therefrom; contact plates on the ends of said rods; and springs on the rods between said plates and uprights; said plates being 50 swiveled on said rods, and said block being adapted to move the ends of said wire to and from said contacts as the block is moved.

55 4. A device for embedding in a wax foundation, strands of wire strung in a frame; comprising a movable block and 60 electric contacts comprising a pair of aper-

tured uprights, rods extending from said uprights and contact plates swiveled to the ends of said rods; and adapted to be contacted with and disconnected from the ends of the wire as the block is moved.

65 5. A device for embedding the wire of a honeycomb frame in wax, comprising a base; a block thereon, electrical contact members, a transformer and a switch, electrical connections between the contact members and transformer and switch, and means permitting disconnection of the electrical connections from said contact members and from said switch and means permitting the contact members to be removed from said base, whereby the device may be disconnected and compactly packed.

70 6. In a device for embedding wire of a honeycomb frame in wax, comprising a block movably mounted; electric contacts and a switch operable otherwise than by the hands for controlling the flow of electricity through said contacts when contacting with said wire.

75 7. A device for embedding wires in a fusible sheet, comprising a base, a block mounted to move in a fixed path on said base, switch members on said base and means on said block for causing said switch members to contact with each other when the block is 80 at one end of its path of travel; and a source of electricity connected with said switch.

8. A device for embedding wires in a fusible sheet, comprising a base, a block movable in a fixed path relative to said base, a 85 rigid and a flexible switch member secured to the base; a member secured to the block and having a sloping surface adapted to ride upon said flexible member to cause the flexible member to contact with the rigid 90 member, when the block is moved to one end of its path of travel, a source of electricity 100 connected with the switch members.

9. In a device for embedding wires in a fusible sheet; a base having a groove there- 105 in; rollers mounted on the base; and a block movably mounted on the rollers, said block having side members projecting into the groove; said block being guided in its movement and prevented from lateral movement 110 relative to its path of movement by the cooperation of the sides of said groove and the side members of the block.

In testimony whereof, I have hereunto set my hand at Los Angeles, California, this 115 6th day of May, 1921.

RICHARD B. REED, JR.

Witness:

JAMES R. TOWNSEND.
